UNITED STATES PATENT OFFICE.

BENJAMIN F. KLEIN, OF ST. PAUL, MINNESOTA.

DESIGN FOR A CABINET.

49,929.

Specification for Design.

Patented Nov. 21, 1916.

Application filed August 17, 1916. Serial No. 115,538. Term of patent 7 years.

To all whom it may concern:

Be it known that I, BENJAMIN F. KLEIN, a citizen of the United States, residing in the city of St. Paul, county of Ramsey, and State of Minnesota, have invented a new, original, and ornamental Design for Cabinets, of which the following is a specification, reference being had to the accompanying drawing, forming part thereof.

Figures 1 and 2 are respectively front and side elevations of a cabinet, showing my new design.

I claim:

The ornamental design for a cabinet, as shown.

BENJAMIN F. KLEIN.

Copies of this patent may be obtained for five cents each, by addressing the "Commissioner of Patents, Washington, D. C."
